UNITED STATES PATENT OFFICE.

EDWIN RUTHVIN OBER, OF WATERBURY, VERMONT.

PIANO-HAMMER.

SPECIFICATION forming part of Letters Patent No. 295,670, dated March 25, 1884.
Application filed May 19, 1883. (Model.)

To all whom it may concern:

Be it known that I, EDWIN R. OBER, a citizen of the United States, residing at Waterbury, in the county of Washington and State 5 of Vermont, have invented a new and useful Piano-Hammer, of which the following is a specification, reference being had to the accompanying drawings.

This invention relates to hammers for vibrating piano-strings, to vibrate the same and cause the sound; and its object is to provide a device possessing superior advantages in point of simplicity, inexpensiveness, durability, and general efficiency.

15 In the drawings, Figure 1 is a perspective view of one of my improved piano-string hammers. Fig. 2 is a vertical sectional view of the same. Fig. 3 is a detail perspective view of the parts separated. Fig. 4 is a perspective view, illustrating a modification.

Referring to the drawings, A designates the block, which carries the hammer proper, and is provided with the usual operating-arm B. To the end of this block A is secured a forked 25 piece, C, between the sides of which a circular hammer-disk, D, is arranged, as hereinabove specified. The piece C comprises a connecting-piece, E, from which projects a screw, F, by which it is secured to the block A, and two side plates, G G, at the end of which are formed disks H, having conical inner surfaces, I, in which are formed central perforations, J, one of which perforations is screw-threaded, 30 as shown.

35 D designates a disk, which forms the hammer, and comprises a hub, L, preferably formed of wood, and a main striking surface or periphery, M, of felt or other suitable material. The hub L is provided with a central perforation, N, that forms a bearing for the disk, and has conical recesses O O formed in its ends, to receive the conical surfaces of the plates G G when the disk is placed between the latter, a suitable textile washer, P, being 40 placed between the surfaces I I and the bottoms of the recesses. A transverse pin or screw, Q, is inserted through the perforations J J and N, and on this screw the disk is adapted to turn.

50 The operation and advantages of my inven-

tion will be readily understood and appreciated. After a portion of the periphery or surface of the rotary disk becomes hardened by usage and contact with the strings, the disk can be easily turned on its bearing to bring 55 another portion of its periphery into play. Thus the whole surface of the disk can be utilized and the hammer is rendered very durable, while the tone is preserved. The disks can, however, be readily removed by simply 60 withdrawing the bearing-screw for substitution or any other purpose. When it is desired that the hammer strike the strings diagonally, it is only necessary to turn the forked piece that carries the hammer, its screw-connection 65 with the block admitting of this movement, when the disk will strike the string as full as if it were on the same longitudinal plane as the string. The conical or concave or convex bearings between the plates and the hub 70 of the disk serve to retain the latter securely in position.

In the modification shown in Fig. 4 of the drawings, the forked piece is dispensed with, and the block A is provided with two upwardly-projecting arms, R R, between which the disk is secured in the same manner, though in this instance it is not capable of a lateral movement to strike the strings diagonally.

I am aware that piano-hammers have heretofore been formed circular and secured between the arms of a forked or bifurcated piece, so that they are capable of an adjustable rotary movement, by which different portions of the periphery are exposed to wear. The forked 80 piece has also been pivotally connected to the head-block, to provide for lateral adjustment in relation to said block to alter the position of the hammer. I therefore do not broadly claim this construction and arrangement of 85 90 parts.

I claim as my invention—

As an improvement in piano-hammers, the combination of the head-block A, the forked piece C, comprising the side plates, G G, having end disks formed with conical inner surfaces, I, provided with a central perforation, 95 and the top connecting-plate, from which projects a screw-threaded shank, F, entering a corresponding recess in the end of the block 100
